US00D874298S

(12) **United States Design Patent** (10) Patent No.: **US D874,298 S**
(45) Date of Patent: ** Feb. 4, 2020

(54) **WATCH**

- (71) Applicant: **Mobvoi Information Technology Company Limited**, Beijing (CN)
- (72) Inventors: **Ke Xie**, Beijing (CN); **Jing Gu**, Beijing (CN)
- (73) Assignee: **Mobvoi Information Technology Company Limited**, Beijing (CN)
- (**) Term: **15 Years**

(21) Appl. No.: **29/623,731**

(22) Filed: **Oct. 26, 2017**

(30) **Foreign Application Priority Data**

Sep. 4, 2017 (CN) 2017 3 0415745

(51) LOC (12) Cl. **10-02**

(52) U.S. Cl. ..... USPC **D10/32**; D14/344

(58) **Field of Classification Search**

USPC D10/1-2, 10, 30-33, 36-39, 98-99, D10/122-124, 126-128, 132; D11/3; D14/344; D24/167, 186
